CLAIM

I claim the ornamental design for a sandal, as shown and described.

DESCRIPTION

FIG. 1 is a front, first side perspective view of a sandal showing my new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The ornamental design that is claimed is shown in the images in the drawings.
